UNITED STATES PATENT OFFICE.

WADE H. ASHER, OF REEDLEY, CALIFORNIA, ASSIGNOR TO JOHN M. CARTWRIGHT,
DOING BUSINESS AS J. CARTWRIGHT & SON.

GRAPE-CUTTING DEVICE.

Application filed November 22, 1926. Serial No. 149,936.

This invention has reference to a device especially designed for use in harvesting grapes or other stemmed fruit, the primary object of the invention being to provide a cutting member which may be positioned over the index-finger of the hand so that the stem of the fruit may be cut simultaneously with the movement of the finger to grip the stem.

10 An important object of the invention is to provide a device of this character which will be strong and durable and one which may be constructed of sheet metal, the design of the device being such that movement of 15 the finger during the cutting operation will not be restricted.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 25 within the scope of what is claimed, without departing from the spirit of the invention.

Referring to the drawing:

Figure 1 is a perspective view of a device constructed in accordance with the invention, the same being shown on the finger of the user.

Figure 2 is a rear elevational view thereof.

Figure 3 is a plan view thereof.

Figure 4 is a sectional view taken on line 35 4-4 of Figure 2.

Figure 5 is a sectional view taken on line 5-5 of Figure 2.

Referring to the drawing in detail, the 40 device includes a finger piece indicated generally by the reference character 5, the same being constructed of sheet metal material and curved to conform to the curvature of the index-finger so that the same may be 45 readily positioned for use.

The upper surface of the finger piece is provided with a cut-out portion 6 to provide a clearance for the knuckle of the index-finger, so that the same may extend there- 50 through and have free movement while in use.

The lower surface of the finger piece is also cut away as indicated at 7, the cut away portion extending to the forward lower 55 edge of the finger piece, defining lateral por-

tions 8 and 9, which, owing to the cut away portion 7, may move laterally with respect to each other when pressure is brought to bear thereon as the index-finger is being bent.

In order that a smooth surface will be provided at the point of contact between the inner surface of the index finger and the finger piece, a lip 10 is provided and secured to the lateral portion 9, the lip being 60 of such a length that it will overlie the cut away portion 7 and rest on the lateral portion 8, as clearly shown by Figure 3.

Ventilating openings such as indicated at 11 are provided for admitting air to the index-finger for the comfort of the user.

The blade forming an important feature of the invention is indicated by the reference character 12 and as shown, is curved to conform to the natural curvature of the 75 index-finger while the same is in the act of cutting a stem.

Teeth 13 are formed along the inner curved edge of the blade, which teeth are designed to cut into the stem of the grapes 80 or fruit being picked to cut the stem from the branch supporting the same.

From the foregoing it will be seen that due to the construction shown and described, a person may position the finger piece over the 85 index-finger and by merely using the index-finger in a manner to pick the fruit as by breaking the stem, the teeth of the blade will cut the stem and the fruit will be released without danger of bruising or dropping the fruit.

It is believed that in view of the foregoing detail description, a further description as to the use of the device is unnecessary.

I claim:

In a device of the character described, a curved tubular body portion formed of resilient material and having a cut away portion extending from one end thereof, a lip formed at one end of the cut away portion and overlying the cut away portion, a portion of the body being free and overlying the body portion defining a finger piece to move with the bending of the finger inserted therein, and a cutting member secured to the body portion.

In testimony that I claim the foregoing as my own, I have hereto affixed my signature.

WADE H. ASHER.
